UNITED STATES PATENT OFFICE

173,078

LAMP BREAK

Dave Patience, Jr., Chicago, Ill., assignor to Rembrandt Lamp Corporation, Chicago, Ill., a corporation of Illinois

Application March 4, 1954, Serial No. 29,354

Term of patent 7 years

(Cl. D48—7)

To all whom it may concern:

Be it known that I, Dave Patience, Jr., a citizen of the United States and resident of Chicago, in the county of Cook and State of Illinois, have invented a new, original, and ornamental Design for a Lamp Break, of which the following is a specification, reference being had to the accompanying drawings forming a part hereof.

Fig. 1 is a front elevational view of a lamp break showing my new design, the dotted lines being for illustrative purposes only;

Fig. 2 is a side elevational view looking at the right of Fig. 1;

Fig. 3 is a rear elevational view;

Fig. 4 is a top plan view; and

Fig. 5 is a side elevational view looking at the left of Fig. 1.

I claim:

The ornamental design for a lamp break, substantially as shown and described.
